(57) **CLAIM**

The ornamental design for a watch strap, as shown and described.

DESCRIPTION

FIG. 1 is a front view of a first embodiment of a watch strap showing my new design;

FIG. 2 is a rear view thereof;
FIG. 3 is a right side view thereof;
FIG. 4 is a left side view thereof;
FIG. 5 is a bottom view thereof;
FIG. 6 is a top view thereof;
FIG. 7 is a perspective view thereof;
FIG. 8 is another perspective view thereof;
FIG. 9 is a front view of the watch strap where the watch strap is in a first configuration of use;
FIG. 10 is a rear view thereof;
FIG. 11 is a front view of the watch strap where the watch strap is in a second configuration of use;
FIG. 12 is a rear view thereof;
FIG. 13 is a front view of the watch strap where the watch strap is in a first detached state;
FIG. 14 is a rear view thereof;
FIG. 15 is a front view of the watch strap where the watch strap is in a second detached state;
FIG. 16 is a rear view thereof;
FIG. 17 is a front view of a second embodiment of the watch strap showing my new design;
FIG. 18 is a rear view thereof;
FIG. 19 is a right side view thereof;
FIG. 20 is a left side view thereof;
FIG. 21 is a bottom view thereof;
FIG. 22 is a top view thereof;
FIG. 23 is a perspective view thereof;
FIG. 24 is another perspective view thereof;
FIG. 25 is a front view of the watch strap where the watch strap is in a first configuration of use;
FIG. 26 is a rear view thereof;
FIG. 27 is a front view of the watch strap where the watch strap is in a second configuration of use;
FIG. 28 is a rear view thereof;
FIG. 29 is a front view of the watch strap where the watch strap is in a first detached state;
FIG. 30 is a rear view thereof;
FIG. 31 is a front view of the watch strap where the watch strap is in a second detached state; and,
FIG. 32 is a rear view thereof.
